UNITED STATES PATENT OFFICE.

WILLIAM JAMES WILSON, OF CHELSEA, MASSACHUSETTS.

COCK OR FAUCET.

SPECIFICATION forming part of Letters Patent No. 308,938, dated December 9, 1884.

Application filed May 20, 1884. (No model.)

To all whom it may concern:

Be it known that I, WILLIAM JAMES WILSON, of Chelsea, in the county of Suffolk, of the Commonwealth of Massachusetts, have invented 5 a new and useful Improvement in Cocks or Faucets; and I do hereby declare the same to be described in the following specification and represented in the accompanying drawings, of which—

10 Figure 1 is a side elevation, Fig. 2 a longitudinal section, and Fig. 3 a transverse section, of a cock or basin-faucet having my invention or improvement, the nature of which is defined in the claims hereinafter presented.

15 In this cock or faucet the handle and the valve-spindle have a ball-and-socket connection, and the handle rests on and is adapted to the screw-cap of the valve-chamber in such manner that when the handle may be laid hold 20 of and pulled down or inclined to the valve-spindle in any direction laterally or longitudinally of the cock, such handle shall exert a leverage or operate as a lever against the cap to raise the valve upward off its seat against 25 the action of the spring, tending to force it down thereupon. From this it will be seen that the movements of the handle are not limited to one plane, but can be made in any plane radial to and passing through the axis of the 30 valve-spindle lengthwise thereof.

I am aware that in cocks or faucets it is not new to hinge or joint the handle to the valve-spindle, so as to enable such handle by being inclined in one plane only radial to the spindle to act as a lever to raise the valve. With such cocks or faucets the handle cannot be turned down or inclined in directions laterally as well as longitudinally of the body of the faucet, as the handle can with my invention, 40 which enables the cocks or faucets having it to be used in situations where the others could not be to advantage.

In the drawings, A denotes the body of the cock or faucet; B, the valve; C, the valve-spindle; D, the operative spring, and E the 45 screw-cap of the valve-chamber, such cap having in its upper part a cup-shaped recess, a, extending around the spindle, and into which for a short distance the lower part of the ball-socket piece G enters when such piece D is 50 drawn by the spring against the top of the cap E. The handle shown at F screws into the said socket-piece G, within the socket b of which is the flat ball H, through which the spindle passes and to which it is fastened by 55 a screw, c, screwed into the spindle, the head of the screw bearing on a collar, d, intervening between it and the ball. That part d' of the socket-piece G which is immediately over the top of the screw-cap E is convex, to enable 60 the piece G while inclined by the handle to slide on the cap a little, as may be necessary, while the valve-spindle is moving rectilinearly.

I claim—

1. The combination of the handle F, the 65 valve-spindle C, and the spring D, with the ball H, fixed on the spindle, and with the socket-piece G, encompassing the ball and resting upon the head or screw-cap of the valve-chamber, all being substantially as set 70 forth.

2. The valve-spindle C, provided at its upper part with the separable ball H, and its fastening-screw c, arranged as represented, in combination with the socketed piece G, surrounding the said ball and secured to the handle, and bearing on the screw-cap of the valve-chamber, all being substantially as represented. 75

WILLIAM JAMES WILSON.
